UNITED STATES PATENT OFFICE

132,602

DESIGN FOR A DOLL

Dayton H. Stewart, Spokane, Wash.

Application October 8, 1941, Serial No. 103,687

Term of patent 14 years

To all whom it may concern:

Be it known that I, Dayton H. Stewart, a citizen of the United States of America, residing at Spokane, in the county of Spokane and State of Washington, have invented a new, original, and ornamental Design for a Doll, of which the following is a specification, reference being had to the accompanying drawings, forming part thereof.

I claim:

The ornamental design for a doll, substantially as shown.

DAYTON H. STEWART.
